(57) CLAIM

The ornamental design for an absorbent wrist band as shown and described.

DESCRIPTION

FIG. 1 is a top perspective view of an absorbent wrist band according to the new design;

FIG. 2 is another top perspective view thereof;

FIG. 3 is a bottom perspective view thereof;

FIG. 4 is a right side perspective view thereof;

FIG. 5 is a left side perspective view thereof;

FIG. 6 is a back perspective view thereof;

FIG. 7 is a front perspective view thereof; and,

FIG. 8 is another bottom perspective view thereof.

The broken lines in the drawings show portions that form no part of the claimed design.
